United States Patent Office

Des. 201,654
Patented July 13, 1965

201,654

BOAT HULL

Rogenald J. Keller, Casco Point, Rte. 1, Wayzata, Minn.

Filed May 4, 1964, Ser. No. 79,803

Term of patent 14 years

(Cl. D71—1)

FIG. 3

FIG. 4

FIG. 5

FIG. 6

FIG. 7

FIG. 1 is a view in top plan of my novel boat hull design;

FIG. 2 is a view in bottom plan thereof;

FIG. 3 is a view in side elevation thereof, the opposite side being a mirror image;

FIG. 4 is a view in front elevation thereof;

FIG. 5 is a view in rear elevation thereof;

FIG. 6 is a transverse section thereof as seen from the line 6—6 of FIG. 1; and

FIG. 7 is a longitudinal section thereof as seen from the line 7—7 of FIG. 1.

I claim:

The ornamental design for a boat hull, as shown and described.
